UNITED STATES PATENT OFFICE.

WILLARD E. BALDWIN, OF CHICAGO, ILLINOIS, ASSIGNOR TO CAROLINE BALDWIN, OF CHICAGO, ILLINOIS.

SHOE-CREASING DEVICE.

No. 902,547.

Specification of Letters Patent.

Patented Nov. 3, 1908.

Application filed April 26, 1907. Serial No. 370,382.

To all whom it may concern:

Be it known that I, WILLARD E. BALDWIN, citizen of the United States, residing at Chicago, in the county of Cook and State of Illinois, have invented certain new and useful Improvements in Shoe-Creasing Devices, of which the following is a specification.

This invention relates to means for performing certain operations on shoes and is 10 hereinafter designated a shoe creasing device.

The object of the invention is to quickly and accurately form creases transversely on the uppers of ordinary shoes in order to give them the appearance that is desired by the 15 trade and the public.

In carrying out my invention I have produced a device consisting essentially of a base, of members to support a shoe while being operated on, and an adjustable device for 20 compressing the foot portion of the shoe in order to effect the creasing operation.

In the accompanying drawings which form a part of my application I have shown a preferred adaptation of my invention in the following views:

Figure 1 is a side elevation of my device showing a shoe in position; Fig. 2 is a top plan view of the device with the shoe removed; Fig. 3 is a longitudinal section taken 30 through the device, and Fig. 4 is an end elevation looking from the front end.

Referring to the details of the drawing 5 represents a base board of suitable dimensions to which is secured a cast iron rack 6 35 the same being arranged centrally of the base board and extending for a portion of its length.

7 is the rear standard which is braced on the base board by braces 8.

40 9 represents a movable standard which is provided with a central opening 10 through which extends a bar 11 projecting inwardly from the rear standard 7 the opening 10 being of considerably greater diameter than the 45 diameter of the bar 11. The upper end of the standard 9 is so shaped as to adapt it to fit the portion of the shoe sole that is under the instep and adjacent to the heel of the shoe.

50 12 represents a shoe which is supported by the standard 9 and has its rear portion fitted against a hollowed block 13 which is fastened by screws 14 to the standard 7. This block 13 is hollowed so that it will con-

form to the general contour of the rear portion of a shoe.

15 represents an adjustable standard of suitable material in the upper portion or head 16 of which is a threaded opening to receive a screw 17 mounted therein. Secured to the inner end of this screw is a block 18 in the face of which is formed an inclined recess 19. Secured to the rear face of the block 18 is a hollowed ring 20 which receives and furnishes a bearing for the flanged end 21 of the screw 17. On opposite sides of the screw 17 openings are formed through the top of the standard 15 in which are slidably mounted guide rods 23 one end of each of which is connected with a block 18 and the other end with a cross head 24 which has an opening to receive the screw 17. On the outer end of the screw 17 is secured an operating handle 22. Extending outwardly from the standard 15 is a foot 27 on the extremity 75 of which is a lug 28 which is adapted to engage the teeth of the rack 6 as clearly shown in Fig. 3. Secured along the opposite edges of the base 5 are strips 26 which overhang the base and form a guide-way and retainer 80 for the lateral extensions 25 of the standard 15 as shown in Fig. 4.

In a device constructed substantially as described, if a shoe is placed in the position shown in Fig. 1, by screwing inwardly the 85 screw 17 the plate 18 will bend upwardly the toe of the shoe and thereby form transverse creases in the shoe upper as indicated.

It will be apparent that the standard is adjustable longitudinally on the rack bar by 90 slightly tilting it so as to disengage the lug from the teeth of the rack bar and sliding the standard over the bar until the proper position is obtained. The guide rods 95 23 prevent the block 18 from turning with the screw 17. The adjustable standard 9 being slidable on the supporting bar 11 permits the standard to be adjusted to a proper position necessary to engage different sizes of shoes. An operator in using this device may 100 use a suitable tool for finishing the creases started by the screwing up of the screw 17.

It will be apparent that various changes may be made in the details of this device without departing from these essential features or principles.

What I claim is:—

1. In a shoe creasing device, the combina-

- tion with a base, of a fixed standard on the base, means supported on said standard for engaging the rear portion of a shoe, an adjustable support for a shoe, and adjustable means for compressing the toe of a shoe.
2. In a shoe creasing device, the combination with a base, of a fixed standard on the base, means supported on said standard for engaging the rear portion of a shoe, an adjustable standard adapted to engage the sole of a shoe and an adjustable device adapted to engage the toe of a shoe, and means for increasing the pressure of said adjustable device against the toe of the shoe.
- 15 3. A shoe creasing device comprising a supporting base an adjustable standard mounted on said base and adapted to engage the sole of a shoe adjacent to the heel and a second adjustable standard supported on said base, a screw mounted in said standard and having a toe engaging piece at its forward end, and means for operating said screw.
- 20 4. In a shoe creasing device, a supporting base having a portion adapted to engage the rear part of a shoe, an adjustable standard

30 mounted on said base and adapted to support the sole of a shoe adjacent to the heel, and an adjustable clamping device comprising a standard, a screw mounted in said standard, means secured to said screw adapted to engage the toe of a shoe, and means for guiding said toe engaging means.

35 5. In a device for creasing shoes comprising a support, a heel engaging means secured to said support, an adjustable standard mounted on said support and adapted to engage the sole of a shoe, a clamping device adjustably mounted on said base comprising a screw adjustable in said standard, a recessed plate secured to one end of said screw and adapted to engage the toe of the shoe, means for operating said screw and guide rods connected with said recessed plate and slidably mounted in said standard.

40 45 In testimony whereof I affix my signature in the presence of two witnesses.

WILLARD E. BALDWIN.
